TOY OSTRICH

Edward Verhoye, 68 Blvd. Vandepereboom,
Courtrai, Belgium

Filed Dec. 23, 1965, Ser. No. 308

Claims priority, application Belgium June 25, 1965

Term of patent 3½ years

(Cl. D34—2)

FIGURE 1 is a front perspective view of a toy ostrich in standing position showing my new design.

FIGURE 2 is a side perspective view from the rear of the toy ostrich in standing position showing the side and back of my new design.

FIGURE 3 is a side perspective view from the front of the toy ostrich in sitting position showing another view of my new design.

I claim:

The ornamental design for a toy ostrich, as shown and described.
